PARALLAX CORRECTION CIRCUIT

Gifford E. White, Hempstead, Robert L. Graef, Brooklyn, and Charles J. La Forge, Hempstead, N. Y., assignors to The Sperry Corporation, a corporation of Delaware

Application June 23, 1944, Serial No. 541,750

10 Claims. (Cl. 235—61.5)

1

This invention relates to an apparatus for correcting gun aiming angles for parallax due to the spacing of the gun station from a control station.

An object of the invention is to provide at a relatively low cost, a compact light weight parallax correcting apparatus suitable for use on airplanes having guns controlled from computing mechanism at a central sighting station.

The desirability of parallax correction is recognized and various devices have been proposed for the purpose of computing parallax correction angles. A parallax correcting system is disclosed in the Italian patent to Zeiss No. 362,981, issued September 14, 1938, and in the abandoned Papello application Serial No. 212,349, filed June 7, 1938, and published May 25, 1943, by the Alien Property Custodian. A parallax correcting apparatus for inter-aircraft fire control is disclosed in the patent application of Knowles and Harris, filed March 1, 1943, Serial No. 477,666, now Patent No. 2,428,372, issued October 21, 1947.

In view of the known prior art of fire control and parallax correction, it is not thought necessary to give here a detailed discussion of the problems involved in determining parallax correction angles, as this subject is known to those skilled in the art.

In one embodiment, the invention contemplates a central station which may be provided with separate port and starboard computing mechanisms, each being controlled by any suitable target tracking device. Switching means are provided by which the respective computing mechanisms may be coupled, if the need therefor arises, to the guns on the opposite side of the craft.

In the embodiment of the invention about to be described, gun aiming data from a computer is transmitted to the gun turrets by suitable means for reproducing angular motion at a distance, a preferred data transmission device being a known type of self-synchronous motor. Differential transformer devices connected in the circuits interconnecting transmitter and receiver self-synchronous motors have their rotary members offset under control of the parallax correcting circuits to effect the required parallax correction of the gun turrets.

The invention will now be described with the aid of the accompanying drawings of which:

Figs. 1 and 2, when placed side by side, show a wiring diagram of an embodiment of the invention;

Fig. 3 is a block diagram showing another form of the invention; and

2

Figs. 4 and 5 show details of transformer windings.

The production of the present apparatus is simplified by the use of standard radio tubes. These tubes have well known characteristics which are fully described in various tube manuals.

In computing fire control data for controlling the directing of a gun mounted on an airplane toward a target, five variables are usually used for accurate determination of the ballistic and prediction corrections. These variables are azimuth, elevation and slant range, air speed and altitude. In addition, the rate of change of the target azimuth, elevation, and range are needed to permit computation of the future position of the target. Gun aiming angles are derived by the computing mechanism from these variables and transmitted to the gun turrets to effect a corresponding positioning of the guns. The parallax computer of the present invention modifies the data transmitted to the gun positions from the control station to compensate for parallax due to the spaced relationship of the central station and gun positions.

In a preferred embodiment of the invention, the computation of correction angles involves the use of electronic circuits and computing transformers. The computing transformers are high impedance transformers which receive their inputs from the data transmission lines of the control station without any noticeable load on them. The outputs from the secondary circuits of these transformers are proportional to the sines and cosines of the control station transmitters in gun azimuth (A_g) or gun elevation (E_g).

Two types of electronic circuits are required. The first is a phase sensitive multiplier circuit which takes two alternating current signals and gives out an alternating current signal whose amplitude is proportional to the product of the amplitudes of the input signals. The second is a reciprocal circuit which takes two alternating current signals and gives out an alternating current signal which is proportional to the ratio of the amplitudes of the input signals.

Uncorrected data comes from the transmitters of the control station to corresponding electrical differential transformers, each having a three-phase rotor and a three-phase stator. The rotary members of the differentials are rotated under control of the parallax correcting circuits according to the proper correction angles, and the corrected data of their outputs are used to control the receiver motors which position the gun or turret. Another rotary transformer is geared

to each set of the electric differentials and measures their position electrically. The output of the rotary transformer is fed back to the servo amplifier input where it bucks the computed correction signal. The difference in signals is fed to the amplifier which in turn operates the servo motor which drives the electric differentials until the differentials have reached their proper positions where the signal difference is zero.

The parallax correction arrangement herein described may be also applied to an automatic gun laying system, or the like, using a radar scanner or any other system where parallax correction is desirable.

One embodiment of the invention contemplates parallax correction as applied to the most practical arrangement of control station and gun turrets wherein the control station and turrets are substantially in alignment along the longitudinal axis of the airplane.

When the control station and turrets are so positioned along the longitudinal axis of the airplane, the azimuth correction angle is closely proportional to the sine of the gun azimuth angle (A_g) divided by the product of the cosine of the gun elevation angle (E_g) and slant range (D_0); and the elevation correction angle is closely proportional to the cosine of the gun azimuth angle multiplied by the sine of gun elevation angle and divided by slant range. The circuits by which these functions are computed electronically will now be described.

In the control station, shown in Fig. 1, coarse and fine azimuth transmitters 20 and 21 have the respective phase windings of their three-phase rotors connected to corresponding phase windings of the three-phase stators 22 and 23 of coarse and fine azimuth differential transformers 24 and 25 of the parallax correcting circuits. The three-phase rotors 26 and 27 of these differential transformers have their respective phase windings connected to corresponding phase windings of the three-phase stators 28 and 29 of coarse and fine azimuth turret receivers 30 and 31. The rotor windings of the turret receivers 30 and 31 are energized from a source of alternating current as are the stators of the computer transmitters 20 and 21.

In the same manner, the elevation transmitters 32 and 33 of the control station are interconnected with the stators of coarse and fine differential transformers 34 and 35, whose rotors are similarly connected to the stators of elevation turret receivers 36 and 37. The rotors of elevation turret receivers 36 and 37 and also the stators of the corresponding elevation transmitters in the control station are energized from a source of alternating current.

Differential transformers 25, 24, 34 and 35 are so constructed that when there is no difference in mechanical position between rotor and stator the transformer ratio thereof is 1:1. When there is no parallax correction, the rotors and stators are thus aligned and the turret receivers will be positioned as though they were connected directly to the transmitters of the control station.

If the differential transformer rotors are rotated through some fixed angle, the new voltages induced in the rotor windings thereof will be the same as the voltages would be in the control station transmitter stator windings if the rotors associated with the latter had been rotated through the same angle. Thus, if the rotors of the differential transformers are rotated through an angle corresponding to the necessary correction

for parallax, the turrets will move away from the position of the transmitter by the corresponding correction angle.

Motors 40 and 41 are controlled by the parallax correction amplifier, described further on. These motors are driven in one direction or the other, and through proper gearing, indicated by dot-dash lines, turn the rotors of the differential transformers through the necessary correction angle, thereby inserting the parallax correction.

The parallax correction circuit has its input connected to the self-synchronous motor circuits through four "trig-function" transformers of novel construction having output functions proportional to sines or cosines of the control station transmitters. The primary windings of the transformers are energized from the wires interconnecting the coarse transmitters of the control station and the differential transformers.

Each of the four trig-function transformers comprises three separate transformer units, the respective primary windings of the transformer units being delta connected and energized by the circuits interconnecting the coarse control station transmitters and the coarse differential transformers. The circuit details of the transformer units are shown in Figs. 4 and 5. The respective secondary windings of each transformer are connected in series, and the turn ratios are such that the magnitude of the output of alternating current is directly proportional to the desired trigonometric functions of the actual A_g and E_g angles and the phase of which (0 or 180 degrees) reverses as the algebraic signs of the functions change.

Referring to Fig. 4, with the described primary connections, where e_1 , e_2 , and e_3 are amplitudes of the A. C. voltage, and θ the angle of rotation of the Selsyn, then in the primary windings of the respective transformer units T_1 , T_2 and T_3

$$\begin{aligned} e_1 &= E \sin \theta \\ e_2 &= E \sin (\theta + 120^\circ) \\ e_3 &= E \sin (\theta - 120^\circ) \end{aligned}$$

and in the secondary windings,

$$\begin{aligned} e_4 &= T_1 e_1 = ET_1 \sin \theta \\ e_5 &= T_2 e_2 = ET_2 \sin (\theta + 120^\circ) \\ e_6 &= T_3 e_3 = ET_3 \sin (\theta - 120^\circ) \end{aligned}$$

and the total secondary voltage

$$e_0 = e_4 + e_5 + e_6 = E [T_1 \sin \theta + T_2 \sin (\theta + 120^\circ) + T_3 \sin (\theta - 120^\circ)] = ET \sin (\theta + \phi)$$

ϕ and T are functions of T_1 , T_2 , and T_3 and can be made any desired values. The particular values of $\phi=0$ and $\phi=90^\circ$ give a sine and a cosine function respectively.

The transformer shown in Fig. 5 is the trig-function transformer 45 for $\sin E_g$. This transformer differs from the other trig-transformers in that each transformer unit is provided with two secondary windings, corresponding windings of each unit being connected in series and one terminal of each of the serially connected windings being joined to the corresponding terminal of the other windings to provide a center tap for a circuit to take care of positive and negative values of $\sin E_g$.

Transformer 45 has the three terminals of its delta connected primary winding connected to elevation Selsyn leads 46, 47 and 48. Its secondary is center-tapped as shown in Fig. 5, and across each section of the output are connected serially connected resistances 49 and 50. Resistance 49 has a resistance of approximately forty

thousand ohms, while that of resistance 50 is ten thousand ohms. The center tap is connected to the secondary winding of transformer 51 whose primary is energized from a source of alternating current. The output of transformer 45 is an A.C. voltage proportional to sine E_g .

A vacuum tube 52 (Fig. 2) known commercially as a "6H6" tube, which is a double diode, has its cathodes 53 and 54 connected by circuits 55 and 56 to the junction points between the respective resistors 49 and 50.

The plate 57 of the diode is connected through a half megohm resistor 59 to the control grid of a vacuum tube 60 of the "6SK7" type. Plate 58 is similarly connected to the control grid of another tube 61, also of the "6SK7" type. The cathodes of both tubes 60 and 61 are connected to ground. An output load network is provided for tube 52 composed of half megohm resistors 62 and 63 and condensers 64 bridged across plates 57 and 58 and connected at its midpoint to ground. Conventional screen grid and suppressor grid connections are employed for tubes 60 and 61. It will be understood that suitable filament circuits are used with the various tubes although none are shown.

The control grids of tubes 60 and 61 are also connected respectively through condensers 65 and 66, and circuit 67 through resistances 68 and 69, of forty thousand and twenty thousand ohms respectively, to opposite terminals of secondary winding 70 of a "trig-function" transformer 71 having a turn ratio such that the magnitude of the secondary voltage is proportional to $\cos A_g$, the primary being energized from the leads 72, 35 73 and 74 which interconnect the azimuth coarse differential transformer with the corresponding transmitter of the control station. With the arrangement just described, the grids of tubes 60 and 61 are energized by voltages proportional to $\sin E_g$ and $\cos A_g$, the output of the tubes being arranged to produce an A.C. current proportional to $\sin E_g \times \cos A_g$. The output circuit of tubes 60 and 61 will be taken up again after the operation of the circuits of tubes 52, 60 and 61 has been described.

Assuming that E_g is zero degrees, then $\sin E_g$, the voltage at the output of transformer 45 is also zero. In this condition, the two cathodes of double diode 52 are always at the same potential with respect to one another. The center tap of the voltage divider 49-49 in the cathode circuit receives an A.C. voltage from transformer 51 with respect to ground. When the cathodes swing negative in potential, the plates of the double diode which are connected to ground through resistances 62 and 63 are at a higher potential than their cathodes and both sections of the diode will conduct. This will cause a voltage drop across the two load resistors 62 and 63, and the condensers 64 associated therewith will charge. Both plates will become negative with respect to ground. The condensers will discharge slightly during the next half cycle when the cathodes swing positive and there is no plate current. In other words, the tube will act as a rectifier and the plate voltages will be D.C. voltages. The magnitude of the negative plate voltages depends on the I.R. drops in resistances 62 and 63, which in turn depend upon the plate currents. The plate current in a diode depends upon the difference in potential between the cathode and plate. Thus, the cathode voltage determines the D.C. plate voltage. Both 75

plate voltages of the double diode 52 are approximately -8 V. when $\sin E_g = 0$.

Assuming now that $\sin E_g$ is not zero, and that the output of transformer 45 is such that during the negative swing of the cathode voltage, the upper terminal of the secondary winding is more negative than the lowermost terminal of the winding. With this condition cathode 53 will go more negative and cathode 54 less negative as the transformer causes an alteration in cathode voltages. As stated above, the cathode voltage determines the D.C. plate voltage, and hence plate 57 will become more negative and plate 58 less negative due to this particular $\sin E_g$. The change in the two plate voltages depends upon the change in cathode voltage, and since this change is proportional to $\sin E_g$, the plate voltage is proportional to $\sin E_g$. If $\sin E_g$ increases, the change in plate voltage increases. If the guns are moved by the transmitters of the control station to the other side of zero degrees, the algebraic sign of $\sin E_g$ changes. In this case, the lower terminal of the secondary winding of transformer 45 will be negative with respect to the upper terminal thereof during the negative swing of the cathode voltage, and now, plate 58 will become more negative, and plate 57 will become less negative. Thus, one plate voltage of the double diode becomes more negative than -8 V. (from transformer 51) by an amount proportional to $\sin E_g$, while the other plate voltage becomes less negative by an equal amount, and which plate is more negative and which plate is less negative depends upon whether $\sin E_g$ is positive or negative.

Tubes 60 and 61 are well known super control amplifier tubes of a type used in many radio sets. The characteristic of this type tube is a remote cut-off with a variable amplification factor. Curves showing the characteristics of this tube may be found in almost any radio tube manual.

The amplification factor can be defined as the ratio of the incremental change in plate voltage to the incremental change in grid voltage which causes it; that is, the change in plate voltage is equal to the change in grid voltage multiplied by the amplification factor. In this type, the amplification factor varies with changes in the grid bias.

Since tube 52 supplies the grid bias for tubes 60 and 61, the effect of $\sin E_g$ on these tubes is to change their bias, and since changing the grid bias changes their amplification factors, the amplification factor of one becomes larger while that of the other becomes smaller, depending upon whether $\sin E_g$ is positive or negative.

The output of trig-function transformer 71 is a voltage proportional to $\cos A_g$. This voltage is used as the A.C. signal voltage applied to the grids of tubes 60 and 61. Since the change in amplification factor is directly proportional to $\sin E_g$, and since the grid signal is $\cos A_g$, the plate voltage of tubes 60 and 61 will vary as the product $(\cos A_g) \times (\sin E_g)$. The bias on one tube will increase, while the bias on the other tube will decrease. In one case, the amplification factor will increase with an increase in $\sin E_g$, and in the other case, the amplification factor will decrease with an increase of $\sin E_g$. Thus, the A.C. plate voltage will increase in one tube, for instance, tube 60, but will decrease in the other tube 61. A difference in the A.C. component will appear on the plates and an A.C. current will flow in the primary winding 80 of transformer 81.

The terminals of primary winding 80 of trans-

former 81 are connected through condenser 82 to the respective plates of tubes 60 and 61. Two fifteen hundred ohm load resistances 83 and 84 are connected between the plates, and their junction point is connected to a source of D. C. potential. This is a conventional arrangement for eliminating the biasing effect of a D. C. plate voltage on the primary winding of a transformer.

The secondary winding 85 of transformer 81 has one terminal connected to the control grid 10 of a tube 87, which is of the "6SK7" type. The opposite terminal is connected through condenser 86 to the cathode of the tube and also through a resistance 88 and circuit 89 to a plate of tube 90 which is a "6H6" double diode. The corresponding cathode of the latter is connected via circuit 92 to the arm 93 of the potentiometer 94 of a range solution device at the control station. The potentiometer is connected through a dropping resistance 95 to a source of A. C. potential.

The cathode voltage of diode 90 is controlled by the operation of the potentiometer, the plate of the diode becoming more negative as the range increases. This plate voltage is used to apply grid bias to tube 87, and since the bias increases as the range (D_0) increases, the amplification factor decreases as the range increases. The circuit is so balanced that the amplification factor varies inversely as the range. Thus, the A. C. plate voltage component of tube 87 (which equals the product of the A. C. grid signal and the amplification factor) is directly proportional to the product: $(\cos A_g) \times (\sin E_g) \times (1/D_0)$.

This is the expression for elevation parallax correction and it includes all of the variables.

A rotary transformer 96 having windings such that its output is a linear A. C. voltage of a magnitude proportional to the angular displacement of its rotor, has its stator energized from a source of A. C. current, and its rotor coupled by suitable gearing, indicated by dash-dot lines, to the differential transformer rotors. The rotor winding of rotary transformer 96 is connected via circuits 98 and 99 to opposite terminals of a twenty thousand ohm potentiometer 100. An eight thousand ohm resistor 101 is included in circuit 98. The arm 102 of the potentiometer is connected to one of the control grids 103 of a vacuum tube 105. The potentiometer can be adjusted to give a matching voltage, which takes into account the distance between the sighting station and the gun station.

Tube 105 is a twin pentode amplifier of the "1644" type each section of which consists of a plate, suppressor, screen and control grids. A common cathode is used for both sections. The cathode is biased through a half megohm resistor. A control grid 108 of tube 105 is resistance coupled to tube 87, reference character 106 indicating the coupling condenser, and 107 a one hundred thousand ohm resistor for grid 108.

The plates 110 of tube 105 are connected to each other and are resistance coupled to the grid 111 of one section of a twin triode amplifier 112 of the "1633" type. Condenser 113 is a coupling condenser which is connected through a one-tenth megohm resistor 114 to grid 111. The grid is grounded through a one-tenth megohm resistor 115.

Tube 112 is a cathode follower stage. The purpose of this tube is to couple the high-impedance output of tube 105 to the low-impedance input transformer of the servo amplifier which will be described later on.

Resistance 120 is a twelve hundred ohm bias resistance for cathode 121 of the input section of tube 112. The plate 122 associated therewith is energized from a source of D. C. through a fifty thousand ohm load resistor 123 and is resistance coupled to grid 124 of the output section through condenser 125, a fifty thousand ohm resistor 126 being the grid resistor. A two thousand ohm resistor 127 is provided in the circuit for cathode 128 which is connected at its ungrounded end through a condenser 129 of large capacity to one terminal of the primary winding 130 of transformer 131, the other terminal of the primary being grounded. With the arrangement just described, the primary winding of the transformer is shunted across resistance 127 and will be energized in accordance with current variations in the resistance which correspond to those appearing at the tube input circuit.

The voltage applied to grid 103 of tube 105 from rotary transformer 96 is 180° out of phase with that of the other control grid 108. This voltage produces an A. C. component in the plate current which varies with the actual parallax correction.

Thus, the total A. C. plate current component through load resistor 116 is the sum of the above two currents. These component currents are 180° out of phase with one another. If they are equal, they balance one another in effect, and there is no actual A. C. current through load resistor 116, and hence no actual A. C. plate current. This is the condition when the actual and computed corrections are equal. When the actual and computed corrections are not equal, the A. C. grid voltages of tube 105 are not equal, the two A. C. components of plate current are not equal, and hence do not cancel. Therefore, under these conditions, there is an A. C. plate voltage which is coupled through condenser 113 and tube 112 to the servo amplifier where it will eventually produce a voltage to operate the elevation correction motor to change the actual correction, making it equal to the computed correction.

The elevation servo amplifier comprises two twin triode amplifier tubes 140 and 141, both of the "1633" type, for the purpose of controlling the operation of the elevation correction motor 41, Fig. 1, to insert the proper correction in the position of the turret. Motor 41 is of a known type and is connected by suitable gearing to the rotors of the elevation differential Selsyns as indicated by dash-dot lines.

Cathodes 150 and 151 of tube 140 are connected to ground through a two hundred ohm resistor 152. Grids 153 and 154 are connected to opposite terminals of secondary winding of transformer 131 for push pull operation. Plates 155 and 156 are bridged by condenser 157 and are connected respectively to grids 158 and 159 of tube 141.

Cathodes 160 and 161 are connected through a four hundred ohm resistor 162 to the ungrounded side of the A. C. supply, which is also connected to grids 158 and 159 through individual twenty-five thousand ohm resistors 163 and 164. Plates 165 and 166 are connected respectively to one terminal of the winding of a relay magnet 167 or 168, whose opposite terminals are grounded. The windings are bridged respectively by condensers 169 and 170.

Relay magnets 167 and 168 operate a balanced armature, shown for purposes of explanation as 75 a double armature 171-172, pivoted at 173 and

174. The armature is spring loaded to assume the neutral position shown when the magnetic circuit is balanced. The armatures operate a current reversing circuit for controlling the operation and direction of motor 41. When either magnet is energized more strongly than the other, the armature will turn on its pivots and an appropriate pair of contacts carried thereby will make with a pair of stationary contacts. Stationary contacts 175 and 176 disposed on opposite sides of the pivot are connected to a source of direct current and cooperate with armature contacts 177 and 178. Similarly, stationary contacts 179 and 180 are grounded and cooperate with armature contacts 181 and 182. The armature members 171 and 172 are connected by circuits 190 and 191 to motor 41. With the arrangement just described, motor 41 will be started in one direction or the other, depending on which magnet 167 or 168 is more strongly energized.

The elevation servo amplifier operates as follows: Both plates 155 and 156 of tube 140 receive a constant A. C. voltage with respect to their cathodes which are connected to ground through resistor 152. The grids of this tube receive an A. C. voltage from transformer 131 when the actual parallax correction is incorrect. The size of the A. C. grid voltage depends upon the size of the error in actual correction. The phase of the A. C. grid voltage depends upon whether the actual correction is too large or too small. Using as a reference the time when the A. C. voltage causes the plates to swing positive with respect to the cathode, one grid, for example, grid 153 will swing positive with respect to the cathode, while the other grid 154 will swing negative with respect to the cathode. Therefore, one half of tube 140 will conduct an appreciable current, while the other half will conduct a much smaller current. Thus, for the conditions assumed the plate current of plate 155 will be large, and that for plate 156 small.

With no A. C. voltage from transformer 131, both plate currents are equal. If the plate current for plate 155 has increased and that for plate 156 decreased, plate 156 becomes higher in potential than plate 155, because the voltage drop through resistor 164 has decreased and the drop through resistor 163 has increased. This happens during each half cycle when the A. C. voltage on plates 155 and 156 causes both plates to swing positive with respect to the cathode. During each half cycle when both plates are negative with respect to the cathode, there is no plate current, irrespective of the grid voltages, and both plates tend to become equal in potential. The condenser 157 connected between the plates charges quickly during the half cycle when there is plate current and it discharges slowly when there is no plate current. Hence, an average or D. C. plate voltage appears between the plates. For the conditions assumed, plate 156 will be at a higher D. C. potential than plate 155 with respect to the junction point of resistors 163 and 164. Therefore, grid 159 of tube 141 which is connected directly to plate 156 will be at a higher D. C. potential than grid 158 which is connected to plate 155, with respect to the cathodes of tube 141.

Both cathodes of tube 141 receive an A. C. voltage from the same source as the plates of tube 140. When the plates of tube 140 are both positive, the cathodes of tube 141 are also positive, and therefore the plates of tube 141, which are connected to the ground through the windings of magnets 167 and 168, are both negative with

respect to their cathodes and no plate current flows in tube 141. During the next half cycle, the plates of tube 141 are both positive with respect to the cathodes, and there is a flow of plate current through the windings of magnets 167 and 168. The size of each plate current is determined by the grid-to-cathode voltages in the tube. For the conditions previously assumed the grid-to-cathode voltage of grid 159 is greater than that of grid 158. Therefore, the current flowing through the winding of magnet 168 to plate 166 will be greater than that flowing through the winding of magnet 167 to plate 165.

When equal currents flow through the windings of magnets 167 and 168, equal forces are applied to the balanced armature and a light spring loading, not shown, keeps the armature in neutral position which is the condition when there is no error in the actual correction.

20 When there is an error, there will be a current in the primary winding of transformer 131 and this will cause an unbalance in the circuits of relay magnets 167 and 168. With the conditions already assumed, the current in the winding of magnet 168 will be larger than in the winding of the other magnet and the armature will be attracted, closing contacts 175 and 177 and also 179 and 181. If, for example, this operation of the relay was due to the actual correction being too large, then the elevation correction motor 41 will rotate in a direction to decrease the actual correction. When all error is removed, there is no A. C. signal from tube 105, the "balancer" stage, to the servo amplifier, and the armature 171-172 30 will assume its neutral position. If the error in the actual correction were in the opposite direction, then the winding of magnet 167 would be the more strongly energized and the opposite set of relay contacts 176-178 and 180-182 would close 35 reversing the polarity of the circuit for motor 41 which would turn in the opposite direction to correct the error.

In Fig. 1 a switching means is indicated by reference character 10 for the purpose of switching the parallax correcting circuit from one computer to another. The computer transmitters of the circuits shown in the drawings are indicated as being associated with a computer "A," while the uncompleted bracketed circuits indicated by the legend are connected to a corresponding circuit arrangement for a computer "B," not shown. The switching device may be of any suitable kind, for example, a relay arrangement or a rotary switch.

55 The azimuth parallax correction circuit solves electronically the function

$$\frac{\sin A_s}{D_s x \cos E_s}$$

60 for azimuth parallax correction in a similar manner. A trig-function transformer 200 has its primary windings connected to the coarse azimuth differential stator circuits 201, 202, and 203. The secondary winding 204 of the transformer is bridged by two serially connected forty thousand ohm resistors 205 and 206 whose junction point is connected by circuit 207 and condenser 208 to the control grid 209 of a super control tube 210 of the "6SK7" type. The output of transformer 200 is an A. C. voltage proportional to $\sin A_s$.

65 The primary winding of trig-function transformer 211 is connected to circuits 46, 47 and 48 of the stator of coarse elevation differential Selsyn 34. The output of this transformer is an A. C. voltage proportional to $\cos E_s$. This voltage

11

is too small to be applied directly to tube 210 so therefore it must be amplified. To this end, one terminal of the secondary winding 212 of the transformer is grounded and the other terminal is connected via circuit 213 to the grid of a triode voltage amplifier 214 which is of the "6J5" type. The output of tube 214 is a voltage proportional to $\cos E_g$, the A. C. component of which is fed through a condenser 215 to a cathode of a double diode 216 of the "6H6" type. The corresponding plate 217 of the diode is connected to ground through a one half megohm resistor, and through another half megohm resistor 219 to the control grid 209 of tube 210. The output from tube 216 is a negative D. C. voltage proportional to $\cos E_g$.

The negative D. C. voltage from tube 216 varies the amplification factor of tube 210 inversely with $\cos E_g$. The A. C. voltage $\sin A_g$ is the grid signal voltage. The A. C. plate voltage of tube 210 varies as the product of the grid voltage and amplification factor and is equal therefore to $\sin A_g / \cos E_g$.

Plate 220 of tube 210 is connected through a load resistor 221 to a source of D. C. potential and through condenser 222 to the control grid 223 of a tube 224 which is similar to tube 210. Control grid 223 is also connected through a half megohm resistor 225 to a plate of range double diode 90. The plate of tube 224 is resistance coupled through condenser 226 to a control grid 227 of double pentode 228, of a type similar to tube 105. From this point on, the elevation and azimuth parallax correction circuits and the apparatus controlled thereby are identical, so the remainder of the elevation correction circuits will be briefly described.

The amplification factor of tube 224 is varied by the negative D. C. voltage from the plate of the range diode 90. It will be recalled that this voltage is directly proportional to range. Since the A. C. voltage on the grid of tube 210 is proportional to $\sin A_g / \cos E_g$, the effect of these grid voltages is to give an A. C. plate voltage component proportional to $\sin A_g / \cos E_g \times D_0$. This is the voltage proportional to the computed azimuth parallax correction.

A rotary transformer 230, similar to transformer 96 has its rotor winding 231 connected by leads 232 and 233 to opposite terminals of potentiometer 234, the adjustable arm 235 of which is connected to a second control grid of tube 228. As in the similar circuits of tube 105 of the elevation correction circuit, the computed correction voltage is compared with the actual correction voltage from transformer 230 and the net output of tube 228 is an A. C. voltage, the magnitude of which depends upon that of the error in correction, and the phase of which depends upon whether the correction was too large or too small. This voltage is coupled through a cathode follower stage comprising a double triode 240 to the primary winding of transformer 241 which is the input for the azimuth servo amplifier. In this amplifier, twin triodes 242 and 243, current reversing relay 244, and azimuth correction motor 40 which is controlled by the relay over leads 245 and 246, all function to effect azimuth parallax correction in the same manner as elevation parallax correction is accomplished by corresponding elements of the elevation circuits.

The circuits just described compute parallax correction where the control station and gun turrets are disposed along a common longitudinal axis of the ship. If the gun turrets were placed in the wings of the airplane or otherwise offset from the zero azimuth axis, the correction cir-

12

cuits must be such as to take into consideration the distance (S) that the turret is spaced from the computer and the azimuth angle (α) at which the turret is displaced from the control station.

Depending on the position of the target with respect to the computer and turret, the gun aiming angles of the computer in azimuth and elevation will differ from those of the turret due to parallax and this difference must be corrected so that the turret guns are aimed at the proper angles.

The azimuth parallax correction angle (ΣA) is equal to the difference between the azimuth angle of the target relative to the gun turret and the azimuth angle of the target relative to the computer (A_g). Likewise the elevation parallax correction angle (ΣE) is equal to the difference between the elevation angle of the target relative to the gun turret and the elevation angle of the target relative to the computer (E_g).

It has been determined empirically that the azimuth and elevation parallax corrections may be approximated as

$$\Sigma A = \frac{S \sin(\alpha - A_g)}{D_0 \cos E_g}$$

and

$$\Sigma E = \frac{S \sin E_g \cdot \cos(\alpha - A_g)}{D_0}$$

These functions are computed electronically in a second embodiment of the invention illustrated by the block diagram of Fig. 3. A block diagram is thought best under the circumstances as the actual circuits of the second embodiment require a substantial duplication of those of Figs. 1 and 2 with similar functions plus two other like circuits for further functions. From what has gone before, it is thought that no difficulty will be experienced in understanding the present embodiment as described in connection with a block diagram.

The present embodiment contemplates self-synchronous control circuits like those of Fig. 1 having correction introduced therein by servo amplifiers as described. Four similar trig-function transformers are used as well as a voltage proportional to range for controlling the inputs to the parallax correction circuits.

In the diagram of Fig. 3, two squares 300 and 301 represent electronic reciprocal circuits, both having an input connected to the voltage source which varies with range (D_0). The output of the $\sin A_g$ trig-function transformer is another input for block 300 while the $\cos A_g$ trig-transformer is the input for reciprocal circuit of block 301. The outputs of the reciprocal circuits are respectively

$$\frac{\sin A_g}{D_0} \text{ and } \frac{\cos A_g}{D_0}$$

The output of the reciprocal circuit of block 300 is connected to an input of an electronic multiplier circuit 302 and to an input of an electronic reciprocal circuit 303. The output of the $\sin E_g$ trig-transformer is connected to an input of multiplier circuit 302 and also to the input of another multiplier circuit 304. The output of multiplier 302 is the product of its two inputs or

$$\frac{\sin E_g \sin A_g}{D_0}$$

The output of the reciprocal circuit of block 301 is connected to an input of a multiplier circuit 304 and also to an input of reciprocal cir-

2,611,537

13

cuit 305. The output of the multiplier circuit is the product of both its inputs or

$$\frac{\sin E_s \cos A_s}{D_0}$$

The actual circuit and its method of operation for determining the latter function is similar to that described in connection with the first embodiment of the invention.

The output of the $\cos E_s$ trig-transformer is connected to a second input of each reciprocal circuit 305 and 303. The output of the former is

$$\frac{\cos A_s}{D_0 \cos E_s}$$

and the latter

$$\frac{\sin A_s}{D_0 \cos E_s}$$

which is the same as that for azimuth parallax correction described in the earlier embodiment and obtained in the same manner.

The outputs of multipliers 302 and 304 are connected to the primary windings of functional transformers 306 and 307 whose turn ratios are proportional to $S_s \sin a_s$ and $S_s \cos a_s$, respectively, the output of the transformers being an A. C. voltage proportional to input voltage and the transformer function.

The transformers 306 and 307 may have single secondary windings where a gun turret is controllable from a single control station. Where a turret is controllable from any of a plurality of spaced control stations, the functional transformers may be modified by providing a corresponding number of secondary windings each having an appropriate turn ratio proportional to $S_s \sin a_s$ and $S_s \cos a_s$ of the turret with respect to the different control stations in order that when the turret is switched from one station to another the circuits will be compensated for changed spacing and relative angular position of the turret and control station.

In the present case it is assumed that two spaced control stations A and B are employed, either of which may be selectively connected to the parallax correction circuit by the operation of switch 10 of Fig. 1.

The parallax corrections ΣA and ΣE are the same as referred to above except that the functions for respective control stations are identified by sub A or sub B and will have different values owing to the spacing of the control stations.

For the two control station arrangement transformers 306 and 307 are shown with two sets of serially connected secondary windings either set being selectively connected in circuit by switch 10.

Secondary winding 315 has one terminal grounded and the other connected through secondary winding 317 of transformer 307 to contact 323 of switch 10 which is closed when the parallax correction circuit is connected to computer B, contact 323 being connected to the azimuth servo amplifier by the switch.

As already stated, the turn ratio of transformers 306 and 307 is such that their output is a voltage proportional to the product of their inputs and $S_s \sin a_s$ and $S_s \cos a_s$ respectively.

Since the input of transformer 306 is

$$\frac{\sin A_s \sin E_s}{D_0}$$

14

then the output is, with the described secondary winding connection,

$$5 \quad S_B \frac{\sin E_s}{D_0} \sin A_s \sin \alpha_B$$

The input for transformer 307 is

$$\frac{\cos A_s \sin E_s}{D_0}$$

10 which when multiplied by the transformer, becomes at the output

$$15 \quad S_B \frac{\sin E_s}{D_0} \cos A_s \cos \alpha_B$$

The combined output voltages of secondary windings 315 and 317 of transformers 306 and 307 added in proper phase is a voltage proportional to

$$20 \quad S_B \frac{\sin E_s}{D_0} \cos (\alpha_B - A_s) \text{ or } \Sigma E_B$$

which is the elevation parallax correction for computer B. This voltage is connected via contact 323 of switch 10 to the elevation servo amplifier input circuit, where it is utilized in the same manner as the voltage from the plate of tube 87 of Fig. 2 for making the required parallax correction.

30 When the A computer is in use, secondary windings 316 and 318 of transformers 306 and 307 are connected in circuit with the elevation servo amplifier by switch 10, windings 315 and 317 being disconnected at this time by the switch. Since the A computer is assumed to have a spacing from the turret differing from that of computer B, the turn ratios of the transformers with secondary windings 316 and 318 in use is proportional to $S_A \sin a_A$ and $S_A \cos a_A$ respectively.

35 The combined output voltages of the transformers is a voltage proportional to

$$40 \quad S_A \frac{\sin E_s}{D_0} \cos (\alpha_A - A_s) \text{ or } \Sigma E_A$$

45 which is the elevation parallax correction for computer A. This voltage is connected via contact 314 of switch 10 to the elevation servo amplifier for use in the same manner as the voltages from secondary windings 315 and 317.

50 The circuits associated with transformers 308 and 309 are generally the same as those of transformers 306 and 307.

55 Transformer 308 has two secondary windings 319 and 320 and transformer 309 also has two secondary windings 321 and 322. Secondary windings 319 and 321 are connected in series, one terminal of winding 319 is connected to contact 325 of switch 10 and a terminal of winding 321 is connected to ground. The secondary windings just mentioned are used in connection with the B computer, and the turn ratios are such that the input voltages are multiplied by $S_B \sin a_B$ and $S_B \cos a_B$ respectively. The primary windings of the transformers are respectively connected to the outputs of reciprocal circuits 305 and 303 whose output voltages are proportional to

$$\frac{\cos A_s}{D_0 \cos E_s}$$

$$\frac{\sin A_s}{D_0 \cos E_s}$$

70 and since the functional transformers multiply their input voltages in accordance with their turn ratios, the output of transformer 309, with the

15

connections described, is a voltage proportional to

$$\frac{S_B \sin A_g \cos \alpha_B}{D_0 \cos E_x}$$

and that of transformer 308 is a voltage proportional to

$$\frac{S_B \cos A_g \sin \alpha_B}{D_0 \cos E_x}$$

These voltages are added together in proper phase and their sum is

$$\frac{S_B \sin (\alpha_B - A_g)}{D_0 \cos E_x}$$

which is the azimuth parallax correction ΣA_B for computer B. This voltage is connected via contact 325 of switch 10 to the azimuth servo amplifier where it is used in circuit arrangement to control the amplifier in the same manner as the voltage from the plate of tube 224, Fig. 2, to effect azimuth parallax correction.

Secondary windings 320 and 322 operate in the manner just described when the A amplifier is in use. With the latter windings in circuit, the turn ratios of transformers 308 and 309 are $S_A \sin \alpha_A$, and $S_A \cos \alpha_A$, respectively, and the sum of their output voltages is

$$\frac{S_A \sin (\alpha_A - A_g)}{D_0 \cos E_x}$$

which is the azimuth parallax correction ΣA_A for computer A. This voltage is connected to the servo amplifier control circuit via contact 326 of switch 10 when the A computer is in use.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. In an aiming system wherein a control device transmits aiming angle data over self-synchronous transmission means to a gun positioning device, the improvement which comprises, in combination, means for deriving from signals transmitted over said transmission means a plurality of different voltages, said voltages being proportional to sines and cosines respectively of azimuth and elevation angle data transmitted over said transmission means, means providing a voltage proportional to range, a device controlled by the range voltage and those proportional to the sines and cosines for deriving voltages proportional to parallax correction angles, transformer means interconnected with the self-synchronous transmission means, and means for controlling said transformer means by the derived voltages to correct the aiming angle data for parallax.

2. In an aiming system wherein a control device transmits aiming angle data over self-synchronous transmission circuit means to a gun positioning device, the improvement which comprises a plurality of transformers energized by signals transmitted over the transmission means having turn ratios adapted to produce output voltages respectively proportional to sines and cosines of transmitted elevation and azimuth aiming angles, means providing a voltage proportional to range, means jointly controlled by

16

the latter voltage and the output voltages of the several transformers for deriving voltages proportional to parallax correction angles for the gun positioning device, rotary differential transformer means in the transmission circuit means adapted with changes in the angular position of the rotary member means thereof to effect a corresponding change in the transmitted aiming angle data, rotary inductive means coupled with the rotary member means of the differential transformer means having linear output voltages, the magnitude of which is controlled by the angular position of the rotary differential transformer means, means for comparing the last mentioned output voltages with those proportional to parallax correction, and means controlled by a difference in said voltages for effecting angular movement of the differential transformer means as well as the rotary inductive means until a difference no longer exists, whereby the differential transformer means are positioned so that the aiming angle data received at the gun positioning device is corrected for parallax.

3. In an aiming system wherein a control device transmits aiming angle data over self-synchronous transmission circuit means to a gun positioning device, the improvement which comprises a plurality of transformers energized by signals transmitted over the transmission means having turn ratios adapted to produce output voltages respectively proportional to sines and cosines of transmitted elevation and azimuth aiming angles, means providing a voltage proportional to range, means jointly controlled by the latter voltage and the output voltages of the several transformers for deriving voltages proportional to parallax correction angles for the gun positioning device, rotary differential transformer means adapted with changes in the angular position of the rotary member means thereof to effect a corresponding change in the transmitted aiming angle data, rotary inductive means coupled with the rotary member means of the differential transformer means having linear output voltages, the magnitude of which is controlled by the angular position of the rotary differential transformer means, means for further adjusting said voltages to compensate for the spacing between said devices, means for comparing the adjusted last mentioned output voltages with those proportional to parallax correction, and means controlled by a difference in said voltages for effecting angular movement of the differential transformer means as well as the rotary inductive means until a difference no longer exists, whereby the differential transformer means are positioned so that the aiming angle data received at the gun positioning device is corrected for parallax.

4. In an aiming system wherein a control device transmits aiming angle data over self-synchronous transmission circuit means to a gun positioning device, the improvement which comprises a plurality of transformers energized by signals transmitted over the transmission means having turn ratios adapted to produce output voltages respectively proportional to sines and cosines of transmitted elevation and azimuth aiming angles, means providing a voltage proportional to range, means jointly controlled by the latter voltage and the output voltages of the several transformers for deriving voltages proportional to parallax correction angles for the

2,611,537

17

gun positioning device, rotary differential transformer means in the transmission circuit means adapted with changes in the angular position of the rotary member means thereof to effect a corresponding change in the transmitted aiming angle data, rotary inductive means coupled with the rotary member means of the differential transformer means having linear output voltages, the magnitude of which is controlled by the angular position of the rotary differential transformer means, means comprising a potentiometer for further adjusting said voltages to compensate for the spacing between said devices, means for comparing the adjusted last mentioned output voltages with those proportional to parallax correction, and means controlled by a difference in said voltages for effecting angular movement of the differential transformer means as well as the rotary inductive means until a difference no longer exists, whereby the differential transformer means are positioned so that the aiming angle data received at the gun positioning device is corrected for parallax.

5. In an aiming system wherein a control device transmits aiming angle data over transmission means to a gun positioning device, a parallax correction circuit comprising means controlled by signals transmitted over the transmission means for producing a voltage proportional to the product of the sine of the elevation angle and cosine of the azimuth angle of the transmitted data, a vacuum tube having its grid energized by said voltage, and a source of negative potential increasing with range for biasing said grid whereby the output voltage of the tube varies as the product of the sine of the elevation angle and cosine of the azimuth angle divided by range.

6. In an aiming system wherein a control device transmits gun azimuth, A_g and elevation, E_g , aiming angle data over transmission means to a gun positioning device, a parallax correction circuit comprising means controlled by signals transmitted over the transmission means for producing a voltage proportional to

$$\frac{\sin A_g}{\cos E_g}$$

of the transmitted angle data, a vacuum tube having a grid circuit energized by said voltage, a source of negative potential increasing with range (D_0), means for biasing said grid from said source whereby the output of the tube is proportional to

$$\frac{\sin A_g}{\cos E_g \times D_0}$$

7. In an aiming system wherein a control device transmits gun azimuth, A_g and gun elevation, E_g , aiming angle data over transmission means to a gun positioning device, means providing a voltage having an amplitude proportional to range (D_0), a parallax correcting system controlled by said voltage and by signals transmitted over said transmission means for deriving voltages proportional to

$$\frac{\sin E_g}{D_0}$$

and

$$\frac{\sin E_g \cos A_g}{D_0}$$

means for multiplying said voltages to obtain product voltages proportional to

$$\frac{S \sin E_g \cdot \sin A_g \cdot \sin \alpha}{D_0}$$

2,611,537

18

and

$$\frac{S \sin E_g \cdot \cos A_g \cdot \cos \alpha}{D_0}$$

5. where S is the distance between the devices and α is the azimuth angle of the gun positioning device with respect to the control device, means for adding the product voltages whereby the sum of the voltages

$$\frac{S \sin E_g \cos (\alpha - A_g)}{D_0}$$

obtained is proportional to the elevation parallax correction voltage, and means comprising adjustable differential transformer means interconnected with the transmission means and controlled by the last mentioned voltage for effecting elevation parallax correction in said angular data.

8. In an aiming system wherein a control device transmits gun azimuth, A_g and gun elevation, E_g , aiming angle data over transmission means to a gun positioning device offset therefrom by the distance S and by azimuth angle α , means providing a voltage proportional to range, D_0 , a parallax correcting system controlled by signals transmitted over said voltage and by said transmitting means for deriving voltages proportional to

$$\frac{\sin E_g}{D_0}$$

and

$$\frac{\sin E_g \cos A_g}{D_0}$$

35. a pair of transformers having turn ratios respectively proportional to $S \sin \alpha$ and $S \cos \alpha$ having their primary windings energized by the respective voltages and their secondary windings connected in series, the combined output voltages of the secondary windings being a voltage proportional to

$$\frac{S \cdot \sin E_g \cos (\alpha - A_g)}{D_0}$$

45. and means comprising adjustable differential transformer means interconnected with the transmission means and controlled by the last mentioned voltage for effecting elevation parallax correction of the aiming angle data.

50. 9. In an aiming system wherein a control device transmits gun azimuth, A_g , and gun elevation, E_g , aiming angle data over transmission means to a gun positioning device offset therefrom by the distance S and by azimuth angle α , means providing a voltage proportional to range, D_0 , a parallax correcting system controlled by signals transmitted over said voltage and by said transmitting means for deriving voltages proportional to

$$\frac{\cos A_g}{D_0 \cos E_g}$$

and

$$\frac{\sin A_g}{D_0 \cos E_g}$$

means for multiplying said voltages to produce resultant voltages respectively proportional to

$$\frac{S}{D_0 \cos E_g} \cdot \cos A_g \cdot \sin \alpha$$

and

$$\frac{S}{D_0 \cos E_g} \cdot \sin A_g \cdot \cos \alpha$$

75

means adding said resultant voltages whereby a voltage

$$\frac{S \sin (\alpha - A_g)}{D_0 \cos E_g}$$

is obtained which is proportional to azimuth parallax correction, and means comprising adjustable differential transformer means interconnected with the transmission means and controlled by the last mentioned voltage for effecting a corresponding correction of the aiming angle data.

10. In an aiming system wherein a control device transmits gun azimuth, A_g , and gun elevation, E_g , aiming angle data over transmission means to a gun positioning device offset therefrom by the distance S and by azimuth angle α , means providing a voltage proportional to range, D_0 , a parallax correcting system controlled by signals transmitted over said voltage and by said transmitting means for deriving voltages proportional to

$$\frac{\cos A_g}{D_0 \cos E_g}$$

and

$$\frac{\sin A_g}{D_0 \cos E_g}$$

a pair of transformers having turn ratios respectively proportional to $S \sin \alpha$ and $S \cos \alpha$ energized by the respective derived voltages, the secondary windings of the transformers being connected in series, their combined output voltages being a voltage proportional to

$$\frac{S \sin E_g \cos (\alpha - A_g)}{D_0}$$

and means comprising adjustable differential transformer means interconnected with the transmission means and controlled by the last mentioned voltage for effecting azimuth parallax correction of the aiming angle data.
